BROW-BAR SUPPORT FOR GOOGLES

Frank W. Lindblom, Cranston, R. I., assignor to
Welsh Manufacturing Company, a corporation
of Rhode Island

Original application December 15, 1948, Serial No.
65,460, now Patent No. 2,507,474, dated May 9,
1950. Divided and this application April 1,
1950, Serial No. 153,400

2 Claims. (Cl. 29—20)

1

This invention is a division of my application, Serial No. 65,460, filed December 15, 1948, now Patent No. 2,507,474, granted May 9, 1950, and relates to a goggle and more particularly to that portion of the goggle which rests against the head of the wearer as a support for the device at this location.

In the manufacture of goggles having supports of this character, there is provided a non-metallic piece of material which is mounted upon a metal rod that extends from one lens to the other, with this non-metallic material at such a location that it will engage the forehead just above the eyes of the wearer to provide a support for the goggles should the goggles be urged toward the face of the wearer. In order to provide such a non-metallic support on the rod, the non-metallic support, if in one piece, must be positioned on the rod prior to the soldering of the rod to each of the rims in which event the solder joint shows as the coloring of the metallic parts of the goggle cannot take place after the non-metallic cushion is positioned without damage to the cushion. Further, if the non-metallic parts are secured on the bar after the parts are secured in position, the cushion must be in two parts and a long and tedious operation of mounting the cushion in place is necessary.

One of the objects of this invention is to provide a device so that all of the metallic parts may be attached and in place and then the non-metallic cushion may be thereafter positioned while in a one-piece tubular form on the metallic rod which receives it.

Another object of this invention is to provide a method of assembly of the non-metallic cushion and the metallic parts of the goggle so that the metallic parts may be colored without the cushion in place and the cushion thereafter assembled by a very simple operation.

Another object of this invention is to speed up the production and reduce the cost of operation in the manufacture of goggles having this type of equipment.

More specifically an object of this invention is to provide a non-metallic cushion which serves as a means for supporting or joining the parts which heretofore served as its support alone.

With these and other objects in view, the invention consists of certain novel features of construction as will be more fully described and particularly pointed out in the appended claims.

In the accompanying drawings:

Fig. 1 is a face view of the goggles;

Fig. 2 is a top plan view thereof with the temples broken away;

2

Fig. 3 is a top plan view of the goggles with the non-metallic cushion removed and illustrating in dotted lines the severing of the stock of the supporting rod;

Fig. 4 is a view similar to Fig. 3 showing in section a cushion being positioned on the supporting rod;

Fig. 5 is a perspective view of a length of stock from which the tube is formed;

Fig. 6 is a perspective view of the tube;

Fig. 7 is a perspective view of the structure of Fig. 6 after being flattened;

Fig. 8 is a section on substantially line 8—8 of Fig. 2 on an enlarged scale.

Fig. 9 is a top edge view of the goggles with the cushion of modified construction in section;

Fig. 10 is a view similar to Fig. 9 showing the cushion being positioned on the supporting rod;

Fig. 11 is a sectional view of the cushion of Fig. 9 alone;

Fig. 12 is a section of Fig. 11 before flattened;

Fig. 13 is a section line 13—13 of Fig. 11.

In proceeding with this invention, I solder the ends of either one or two pieces of a metal supporting rod to the upper edge of the rims of the goggles which is to serve as a support for the cushion, and then the goggle is colored or plated to provide a good finish on the same. Thereafter, a cushion is provided with tubular ends, the rod is severed if previously in one piece to provide two bars, and the cushion is slid onto one of the bars a sufficient extent so that the other bar may be received. The bar is then moved back into alignment with the other bar and the cushion then slid back over the other bar and cemented in place. Out-of-round sections are provided for preventing rotation of the cushion on the bars.

With reference to Figs. 1—8 of the drawings, 10 designates the lens rims which are joined together by the bridge 11 upon which arms 12 are provided for supporting nose pads 13 which nose pads may be of non-metallic material. End pieces 14 are formed on the outer edges of the rims from which temples 15 extend rearwardly.

A support for engaging the brow of the face of the wearer above the eyes is designated generally 16 and consists of a rod 17 (see Fig. 3) which is soldered or otherwise suitably secured as at ends 18 and 19 to the rims 10; and the frame is then plated or colored to provide a suitable finish; and, thereafter, the rod 17 is severed at 20 so as to provide a bar 21 attached as at 18 and a bar 22 attached as at 19 which bars extend toward each other and are in general alignment after severing. The location of severing will be such that the bar 22 is of a length to receive the cushion.

A cushion formed of some non-metallic material, such as Celluloid, is available in solid rod form, designated generally 23 in Fig. 5, and may be formed into a tube, as designated at 24 in Fig. 6, having a bore 25 extending therethrough. This may be accomplished by a screw machine operation by drilling in through the opposite ends of the rod; and, thereafter, the tube 24 will be flattened, as shown at 26 in Fig. 7, so as to provide a somewhat oval hole 27 through the same (see also Fig. 8). The bars 21 and 22 or rod 17 will be rectangular or of some shape, such as designated 28 in Fig. 8, so that when the cushion 26 is positioned on these bars it cannot rotate.

To assemble the cushion 26 on the structure, as described above, it is merely necessary to raise the bar 22 outwardly from alignment with the bar 21, as shown in Fig. 4, and slide the cushion 26 over the end of the bar 22 into a position, such as shown in dotted lines in Fig. 4. Then, the bar 22 may be moved back into alignment with the bar 21 and the cushion 26 slid back over the ends of the bars 21 and 22 to the position shown in Figs. 1 and 2 with the longest axis of the oval hole 27 substantially in the plane of the rims. Cement will then be applied to maintain the non-metallic Celluloid cushion 26 in the position which it has been moved to on the bars. The cushion thus serves to connect the bars together and provides its own support for the bars in maintaining the desired rigidity of this support which may rest against the face of the wearer.

With reference to Figures 9 to 13, the rims 10 have bars 30 and 31 soldered to each of the rims as at 32 and 33, these bars being spaced a considerable distance between their inner ends 34. A cushion bar 36 of the same soft material, such as Celluloid or the like, is formed originally in a round shape as at 37 in Figure 12 and had bores 38 and 39 formed in its opposite ends, as shown more particularly in Figure 11 to receive the ends 34 of the bars 30 and 31. Thus, in positioning this cushion 36 in place, it will be positioned on the bar 30, as shown in Figure 10 and slid so that

the bottom of its bore 38 will engage the end of the bar 30, the bore 38 being of such a depth that when the cushion 36 is swung inwardly from the position shown in Figure 10 to that shown in Figure 9, the bar 31 may be received in the bore 39. Thus, as the cushion 39 is swung inwardly, the bar 31 is moved into the bore 39 and the cushion adjusted on the bars 30 and 31 until it assumes a position shown in Figure 9.

In some cases the cushion 36 instead of being cylindrical, as shown in Figure 12, may be flattened, so as to take the out-of-round shape 40, as shown in Figure 13, in which case the opening or bore will be flattened as at 41, and in this case the bars 30 and 31 will be of a similar out-of-round shape to fit into this bore and prevent rotation of the cushion on these bars.

I claim:

1. The method of forming a cushioned support on a goggle having two connected lens rims which comprises soldering a rod at its ends to said rims and then cutting the rod intermediate its end to provide two bars, springing one bar out of line with the other and sliding a tube thereon, then aligning said bars and sliding the tube over the end of the other bar.

2. The method of forming a cushioned support on a goggle having two connected lens rims which comprises soldering a rod at its ends to said rims and then cutting the rod intermediate its ends at one side of the middle to provide two bars, springing the longer bar out of line with the other and sliding a cushion tube thereon, then aligning said bars and sliding the tube over the end of the other bar.

FRANK W. LINDBLOM.
